2 SHEETS—SHEET 2.

UNITED STATES PATENT OFFICE.

WILLIAM ALONZO RHINESMITH, OF UPPER MACOPIN, NEW JERSEY.

RAILWAY-TIE.

1,148,051.

Specification of Letters Patent. Patented July 27, 1915.

Application filed August 25, 1914. Serial No. 858,496.

To all whom it may concern:

Be it known that I, WILLIAM ALONZO RHINESMITH, citizen of the United States, residing at Upper Macopin, in the county of Passaic and State of New Jersey, have invented certain new and useful Improvements in Railway-Ties, of which the following is a specification.

This invention relates to railway ties and has as its object to provide a metallic railway tie which will possess numerous advantages adapting it for use as a substitute for the ordinary wooden tie and without sacrificing any of the advantages possessed by a wooden tie.

It is one aim of the invention to provide a metallic tie which will be resilient practically to the same degree as the ordinary wooden tie, the tie being so constructed as to be yieldable although it embodies no cushioning means such as a spring.

Another aim of the invention is to provide a tie embodying shimming means readily and quickly adjustable in accordance with the road bed and track conditions. The ordinary method of shimming consists in working and filling in the ballast so as to elevate the rails which have become depressed or the outer rails on a curve, but this requires considerable time and labor and must be frequently done in order to maintain normal track conditions. The present invention therefore aims to provide a tie embodying in its structure means which may be adjusted by a track walker to adjust the end of the tie to proper elevation in the event of displacement of the tie.

Another aim of the invention is to provide novel means for preventing lateral displacement of the tie and means for connecting a number of the ties together to further prevent their relative displacement or individual lateral displacement.

The invention also aims to provide a tie embodying means whereby the rails supported thereby may be properly clamped in place to space their treads at the proper gage regardless of the dimensions of their base flanges.

The invention also has as its object to provide a tie so constructed that a water trough may be arranged upon a desired number of the ties to permit of water being taken up by a locomotive while running.

Another aim of the invention is to provide a tie which will be light in weight and

consequently adapted to be readily transported at low cost and capable of being readily and conveniently handled by the workmen laying the track.

In the accompanying drawings: Figure 1 is a perspective view of the tie embodying the present invention. Fig. 2 is a vertical longitudinal sectional view therethrough, the tie being arranged for use in a straight line of track. Fig. 3 is a similar view, but illustrating the tie adjusted for use on a curve. Fig. 4 is an end elevation of the tie. Fig. 5 is a vertical sectional view on the line 5—5 of Fig. 2. Fig. 6 is a view partly in elevation and partly in longitudinal section of one end of the tie, illustrating the means provided for holding the body and base of the tie against relative movement. Fig. 7 is a side elevation of several of the ties, illustrating the manner in which they may be connected in alinement.

Corresponding and like parts are referred to in the following description and indicated in all the views of the accompanying drawings by the same reference characters.

In the drawings, the tie is illustrated as comprising a body preferably formed from a single piece of sheet metal of requisite thickness, and this body includes a flat top 1 and vertical sides 2. The rails which are to be supported by the tie are indicated by the numeral 3 and have their base flanges disposed directly upon the top 1 of the body of the tie, the rails being held in place by means of rail clamps 4 and 5 secured by means of bolts 6 to the said top of the body. The rail clamps 4 are located at the inner sides of the rails and clamp the inner base flanges of the rails, whereas the tie plates 5 engage the outer edges of the outer base flanges and against the outer sides of the webs of the rails.

Between the rail clamps 4 and 5, the top 1 of the tie body is rolled or otherwise formed with a depressed portion 3' forming a seat 3^a which is of a depth to receive the base flange of the respective rail, the seat extending at right angles to the length of the tie body and the upper face of the base flange of the rail being substantially flush with the upper surface of the said top 1. The seat 3^a is, however, of greater width than the width of the ordinary rail base and in order that the rails supported by the ties may be adjusted so that their treads will be spaced apart at the proper gage, re-

2
 gardless of the width of the rail bases, spacing bars 4^a are provided and are adapted to be disposed within the seats 3^a between one or the other of the edges of the respective rail base and the corresponding side wall of the seat. For example, if the rail bases are relatively narrow, the spacing bars 4^a of each tie are arranged to lie between the inner or opposing edges of the bases of the rails supported by the tie and the inner side walls of the rail seats 3^a, and if the base flanges are relatively wide, these strips are arranged at the opposite side of the flange and between the same and between the other or outer side walls of the rail seats. These spacing bars 4^a may be of various widths, so as to provide for the proper spacing of various sizes of rails and in order that the bars may be securely held in place, their ends are struck down, as indicated by the numeral 4^b, so as to extend down beside the sides 2 of the tie body and the bars are furthermore overlapped by the rail clamps 4 or 5, as the case may be, whereby to provide against their upward displacement from the rail seats.

The base of the tie consists of two base members pivotally connected with the body of the tie at a point between the ends thereof and independently angularly adjustable or movable with respect to the said body of the tie. Each of these base members is preferably formed from sheet metal and each comprises a bottom 7 and sides 8 which occupy planes at right angles to the plane occupied by the bottom 7 and which are provided along their upper edges with inwardly projecting relatively narrow flanges 9. The base members are arranged to fit between the sides 2 of the tie body and their sides are of such height that when the bottoms 7 of the base members are horizontal and in a plane with the lower edges of the sides 2 of the body, the flanged upper edges of the said members will contact with the under side of the top 1 of the body. In their assembled position, the adjacent or inner ends of the bottoms 7 of the base members are slightly spaced apart and the corresponding ends of the sides 8 of the said base members are in overlapped relation, as clearly shown in Figs. 2 and 3 of the drawings.

In order to pivotally connect the base members with the body of the tie, a bolt rod 10 is fitted through the sides 2 of the body and through the overlapped inner ends of the sides 8 of the base members at a point adjacent the bottom of the tie. It will now be apparent that the base members may be adjusted angularly upon the bolt rod 10 as a pivot, independent of each other and with relation to the respective ends of the tie body, and it is contemplated that in one embodiment of the invention one of these

base members shall be adjustable with relation to the respective end of the tie body and held in such adjustment, and that the other base member shall be freely movable angularly with relation to the other end of the tie body.

While, as stated above, the base members are movable with relation to the tie body, it will be apparent that when the tie is disposed in the road bed, the base members will remain stationary and that the tie body may have slight yielding or tilting movement with respect thereto as weight is imposed upon the rails due to the passing thereover of a train. In order that the thrust of the rails may be borne directly by the base members and thereby transmitted to the road bed, a supporting member is provided beneath each end of the top 1 of the body of the tie. Each of the supporting members comprises a top 11, sides 12 and a bottom 13, the members being hollow and open at their ends. The bottom 13 of each supporting member is preferably of greater length than the top 11 thereof so as to insure of firm support of the rail. The supporting member at one end of the tie has its top 11 and bottom 13 located in parallel planes as also its sides, and this member, indicated in general by the reference character A in Figs. 2 and 3, has its top 11 secured to the under side of the top 1 of the body of the tie by means of the bolts 6 which secure the adjacent rail to the tie, and when the base member at this end of the tie is in the position shown in Figs. 2 and 3 of the drawings, or, more specifically speaking, when the respective end of the tie is in the position shown in these figures with relation to the said base member, the bottom 13 of the said supporting member will rest upon the bottom 7 of the said base member. Each supporting member has its top 11 formed with a depression forming a seat 11^a to receive the respective depression 3' in the top 1 of the tie body. The other supporting member, indicated in general by the reference letter B, has its sides parallel and is secured to the under side of the top of the rail body in the same manner as the supporting member A. The bottom of this member B, however, occupies a plane at an angle to the plane occupied by the top of the said member and is formed with transversely extending corrugations 14 which extend in a series from one end to the other of the said bottom.

As will be pointed out, the corrugated bottom of the member B constitutes one element of the shimming device provided in connection with the rail. The shimming device, above mentioned, further includes a shimming block 15 which is wedge-shaped and has its upper side formed with a series

of transversely extending ribs 16 arranged to interchangeably fit the corrugations in the bottom 14 of the supporting member B. By reference to Figs. 2 and 3 of the drawings, it will be observed that the shimming block 15 is adapted to be adjusted longitudinally of the tie between the bottom 14 of the supporting member B and the bottom of the respective base member, and it 5 will be apparent that as the shimming block is moved inwardly, or in other words, adjusted toward the center of the tie, the corresponding end of the tie body will be adjusted vertically. In order that the shimming block may be securely held in adjusted position, it is provided at its major or outer end with a shank 17 which projects toward the adjacent end of the tie and which is formed with a longitudinally extending slot 18 through which the bottom of the base member is secured a set bolt 19. In order that the supporting members 10 may have movement with respect to the base members without interference on the part of the flange 9, these flanges are cut away at the points of location of the said supporting members as indicated by the numeral 20, so as to receive the sides of the said supporting members.

15 From the foregoing description, it will be understood that with the parts in the position shown in Fig. 2, the tie is adapted to be laid in a straight line of track, inasmuch as it is supported in level position. When 20 the tie is to be laid in a curve, however, the shimming block 15 is adjusted inwardly so as to elevate the corresponding end of the tie body to such a degree as to support the outer rail to the proper elevation above the inner rail, and it will also be apparent that the said block may be adjusted as often as necessity arises in order to maintain the proper relative elevation of the inner and outer rails.

25 As a means for preventing lateral displacement of the tie, there is provided an anchoring member comprising a body 21 having a flat bottom 22 and upwardly inclined sides 23, the said body preferably 30 having a transversely curved upper side. The body 21 is provided at each end with an upstanding ear 25 and these ears are provided with openings receiving the bolt rod 10, the body being in this manner supported beneath the under side of the tie. It will be observed by reference to Figs. 2 and 3 of the drawings, that the body is wider at its bottom than at its top and consequently it serves not only to prevent lateral displacement of the tie but also tends 35 to prevent upward displacement thereof when embedded in the road bed.

40 In order to reinforce the supporting members they are provided in each corner 45 with diagonal braces 26. It will be under-

stood that inasmuch as the tie is hollow and open at its ends and its said ends are exposed when the tie is properly placed in the ballast, any accumulation of water at either side of the road bed may drain 50 through the ties. It will also be understood that when a greater weight is imposed upon one end of the tie than upon the other end thereof, the first-mentioned end of the tie body may have a slight downward yielding 55 movement and the other end of the body may move upwardly a corresponding distance, and that this movement of the last-mentioned end of the body is with relation to the corresponding base member inasmuch 60 as the base members are stationary. The upward movement of the last-mentioned end of the body does not permit of pieces of the ballast lodging beneath the tie at this end, however, for, as stated, the base 65 members remain stationary and serve to retain the ballast in normal condition.

65 In the event that it is desired to secure the ends of the tie body against movement with respect to the corresponding base members, sectional tie-bars may be employed, as 70 illustrated in Fig. 6. Each of these tie-bars comprises a pair of sections 27, each section having a hooked end 28 engageable in a slot 29 in the top of the body or bottom of the base member, as the case may be, and the overlapping portions of the sections are secured at adjustment by means of a set bolt 30, one of the sections being formed with a slot 31 to permit of such adjustment 75 of the said sections.

75 In order that a water trough may be supported by a number of ties to extend between the rails and in position to permit of water being taken up by a locomotive 80 while running, a number of the ties in a line of track are formed between their rail supporting portions with depressions 32 in which the water trough, indicated at 33, is disposed or secured, these depressions being formed in the tops 1 of the tie bodies. In the instance of ties provided with these 85 depressions 32, the sides of the base members are cut-away, as indicated at 33, at their inner upper corners so as not to interfere with the depressed portion of the tie body.

90 Having thus described the invention, what is claimed as new is:

1. A railway tie comprising a body, and a base for the body comprising sections independently angularly adjustable with respect to the body.
2. A railway tie comprising a body, and a base for the body comprising sections with respect to which the body is relatively angularly adjustable.
3. A railway tie comprising a body, and a base for the body comprising sections for supporting the ends of the body, the sections

being adjustable to support the ends of the body at different elevations.

4. A railway tie comprising base sections independently angularly adjustable, and a body supported upon the sections.

5. A railway tie comprising base sections, and a body, the base sections being pivotally connected to each other and to the said body.

6. A railway tie comprising base sections, 10 a body, the base sections being pivotally connected to each other and to the said body, and means for relatively adjusting one end of the body with respect to the corresponding base section.

15 7. A railway tie comprising pivotally connected base sections relatively angularly adjustable, and a body supported at its ends upon the said sections.

8. A railway tie comprising a body and a 20 base, the body having a supporting member provided with a series of seats, and a shimming block provided with a corresponding series of projections, the shimming block being disposed between the said support and 25 the said base.

9. A railway tie comprising a body and a base, the body having a supporting member provided with a series of seats, a shimming block provided with a corresponding series 30 of projections, the shimming block being disposed between the support and the base, and means for holding the block at adjustment.

10. A railway tie comprising a body and a 25 base comprising sections with respect to which the ends of the body are angularly ad-

justable, and shimming means disposed between one end of the body and the corresponding base section.

11. In a railway tie, a body, an anchoring 40 member comprising a body disposed beneath the tie body and having apertured portions extending beside the sides of the said body, and a bolt rod fitted through the tie body and through the said apertured portions. 45

12. A railway tie comprising a body, having a top and sides, a base for the body with respect to which the body is angularly adjustable, and a supporting member interposed between the top of the body and the 50 said base, the top of the body and the top of the supporting member having interfitting depressions and the depressions in the top of the body constituting a rail seat.

13. A railway tie comprising a hollow 55 body formed in its top with a depression located beneath its ends and arranged to receive a water trough.

14. A railway tie comprising a hollow body having a top and spaced depending sides, and a base for the body comprising sections pivotally supported between the sides of the body and independently angularly adjustable with respect to the ends of the body, whereby to support the ends of the 60 body at various elevations. 65

In testimony whereof I affix my signature in presence of two witnesses.
